Primary Examiner — Shannon W Morgan*Assistant Examiner* — Ieisha N Price(74) *Attorney, Agent, or Firm* — Dunlap Bennett & Ludwig, PLLC(57) **CLAIM**

The ornamental design for a lashing bar, as shown and described.

DESCRIPTION

FIG. 1 is a perspective view of a lashing bar, showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a perspective view of the lashing bar, shown in use. The evenly-sized dash-dash broken lines showing support bars in FIG. 8 depicts environmental subject matter that forms no part of the claimed design, while the remaining evenly-sized dash-dash broken lines shown in the drawings depict portions of the lashing bar that form no part of the claimed design.

The unevenly-sized dash-dot-dash broken lines depicts the boundary of the claim that forms no part of the claimed design.
